(57) **CLAIM**

The ornamental design for a robot and/or toy robot and/or mobile phone, as shown and described.

DESCRIPTION

FIG. 1 is a front perspective view of a robot and/or toy robot and/or mobile phone showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

(Continued)

FIG. 9 is a front perspective view of a second embodiment thereof;
FIG. 10 is a rear perspective view thereof;
FIG. 11 is a front view thereof;
FIG. 12 is a rear view thereof;
FIG. 13 is a top plan view thereof;
FIG. 14 is a bottom plan view thereof;
FIG. 15 is a right side view thereof; and,
FIG. 16 is a left side view thereof.

The drawings include shadows and reflections which indicate contour, not surface ornamentation.

The areas within the broken lines illustrate portions of the robot and/or toy robot and/or mobile phone which form no part of the claimed design.

1 Claim, 8 Drawing Sheets
